ABSTRACT OF THE DISCLOSURE

Sulfonated derivatives of novel detergent alkylate compositions exhibiting superior synergistic detergent characteristics comprise mixtures of secondary C_{11} and C_{15} sulfonated phenyl-n-alkanes in a weight ratio of from 1:10 to about 4:1, respectively.

BACKGROUND OF THE INVENTION**Field of the invention**

This invention relates to the field of synthetic detergent compositions and, more particularly, to biodegradable, synergistic mixtures of sulfonated phenyl-n-alkane detergent compositions.

Prior art

In recent years, a significant emphasis has been placed upon finding suitable detergent compositions which do not deleteriously affect the ecological balance of water bodies used for receiving treated or untreated municipal and industrial waste. As a result, biodegradable sulfonated phenyl-n-alkanes have been substituted on a large commercial basis for the less biodegradable branched-chain alkylbenzene sulfonates. Much effort and research have been devoted to developing sulfonated phenyl-n-alkane mixtures approaching or equalling the high detergent efficiency of the alkylbenzene sulfonates. For example, U.S. 3,340,141, and Ser. No. 676,707, filed Oct. 20, 1967, disclose detergent alkylate and sulfonated detergent alkylate compounds which exhibit high detergency characteristics comprising mixtures of secondary phenyl-n-alkanes containing 11 to 14 carbon atoms in the alkane portion of the molecule. In particular, these mixtures are low in 2- and 3-phenyl-n-alkane isomers which impair detergency effectiveness. As indicated in the aforementioned patent, it is known that the C_{11} sulfonated phenyl-n-alkanes show very poor detergency. In addition, heretofore the C_{15} sulfonated phenyl-n-alkanes have not shown acceptable detergency characteristics. In fact, most references in the art prefer and are limited to mixtures of C_{12-14} sulfonated phenyl-n-alkanes.

SUMMARY OF THE INVENTION

Surprisingly, we have now found that mixtures of secondary C_{11} and C_{15} sulfonated phenyl-n-alkanes exhibit excellent synergistic detergency which is not expected or predictable from their individual detergency characteristics. In particular, the novel compositions of the present invention comprise mixtures of sulfonated phenyl-n-alkanes containing secondary C_{11} and C_{15} sulfonated phenyl-n-alkanes in a weight ratio of from about 1:10 to 4:1 and, preferably, 1:4 to 1.5:1. More preferably, the C_{15} sulfonated phenyl-n-alkane portion is low in the 2- and 3-phenyl isomers.

In addition, the C_{11} and C_{15} components may be combined within the described ratio with other satisfactory sulfonated phenyl-n-alkanes detergents, with no adverse effect on the overall detergency. That is, for example, an excellent detergent composition may contain 30 percent of secondary C_{11} and C_{15} sulfonated phenyl-n-alkanes

2

in the proper proportions, and 70 percent of a mixture of $C_{12-C_{14}}$ sulfonated phenyl-n-alkanes low in the 2- and 3-phenyl isomers.

DESCRIPTION OF DRAWING

5

The figure graphically depicts the observed synergistic effect of mixtures of C_{11} and C_{15} sulfonated phenyl-n-alkanes as compared to the predicted effect.

DETAILED DESCRIPTION OF INVENTION

The secondary phenyl-n-alkanes utilized in the present invention may be prepared by conventional methods as known in the art. These methods include the alkylation of benzene or its derivatives, such as toluene and xylene, with n-alkenes or n-haloalkanes containing from 11 to 15 or more carbon atoms. The n-alkenes or n-haloalkanes may be derived from distillate cracking or wax cracking, catalytic dehydrogenation of n-alkanes, chlorination-dehydrochlorination of n-alkanes, ethylene polymerization and chlorination of n-alkanes. In addition, the raw materials from which the straight-chain stock is to be derived may be subjected to iso-normal separation processes, such as molecular sieves, and urea clathration to produce a more linear product than can otherwise be obtained.

After alkylation of the benzene ring or its derivative, the aromatic portion is sulfonated by known methods with such agents as chlorosulfonic acid, sulfur trioxide, and oleum, etc.

The mixtures of secondary C_{11} and C_{15} sulfonated phenyl-n-alkanes may be directly used as the active ingredient to form excellent detergent compositions, or may be beneficially combined with mixtures of other sulfonated phenyl-n-alkanes. In the latter use where the other sulfonated phenyl-n-alkanes are superior in dishwashing ability to the secondary C_{11} and C_{15} mixture, the C_{11} and C_{15} component may range from as much as 30 to 40 percent and, preferably, from 5 to 20 percent by weight of the active ingredient of the detergent composition. However, where the other sulfonated phenyl-n-alkanes are equivalent or less in dishwashing ability, there is no limitation on the amount of the C_{11} and C_{15} utilized. Preferably, the C_{11} and C_{15} mixtures are combined with $C_{12-C_{14}}$ mixtures low in the 2- and 3-phenyl isomers. In effect, the incorporation of C_{11} and C_{15} mixtures into other sulfonated phenyl-n-alkanes often increases the average molecular weight, broadens the acceptable range of usable phenyl-n-alkanes and, accordingly, provides significant economic advantages and incentives.

The secondary C_{11} sulfonated phenyl-n-alkane component may comprise isomers containing internal phenyl attachment (4-, 5-, and 6-isomers), end phenyl attachment (2-, and 3-isomers) or a distribution over the whole isomer range. All distributions of the C_{11} isomers exhibited the excellent synergistic effect upon combination with the C_{15} compound.

The C_{15} sulfonated phenyl-n-alkanes also showed excellent synergism for the end phenyl attachment (2-, and 3-isomers) and for distribution over the whole range of isomers. Surprisingly, however, the internal phenyl attachment (5-, 6-, 7-, and 8-isomers) exhibited substantially increased synergism over the end and whole isomer distributions. In general, mixtures of C_{15} sulfonated phenyl-n-alkanes containing at least 70% by weight of internal isomers and preferably from 80 to 90% showed this increased synergism.

In general, the ratio of C_{11} to C_{15} sulfonated phenyl-n-alkanes may vary from about 1:10 to about 4:1, respectively. Preferably, however, the ratio ranges from 1:4 to about 1.5:1.

Additional compatible ingredients may be incorporated into the detergent compositions prepared in accordance

with the present invention to enhance their detergent properties. Such ingredients may include, but are not limited to, anticorrosion, anti-redeposition, bleaching and sequestering agents, optical whiteners and certain organic and inorganic alkali and alkaline earth salts, such as inorganic phosphates, sulfates, carbonates or borates, and the organic salts, such as sulfosuccinates, xylene sulfonates, and the alkali metal salts of polycarboxylic acids; e.g., trisodium salt of nitrilo triacetic acid, tetrasodium salt of ethylenediaminetetraacetic acid, etc.; and the sodium salt of the copolymer of maleic anhydride and ethylene. The appropriate quantities and compositions of these additives, agents and builders are well described in the art.

An effective means for evaluating the detergative characteristics of detergent compositions is known as the "Hand Dishwashing Test" which is based on a procedure presented at the ASTM D-12 Subcommittee on Detergents, Mar. 10, 1949, New York, N.Y. The test measures, under simulated home washing conditions, the number of plates or dishes washed before the foam collapses. This test was utilized to evaluate the improved performance of the disclosed detergent compositions.

Detergent formulations were prepared from the sulfonated phenyl-n-alkane mixtures of the present invention, water and other ingredients. The formulations were adjusted until the percentage of sulfonated phenyl-n-alkanes equalled about 25 percent by weight of the total detergent formulation.

In the following examples, the concentrations employed in the "Hand Dishwashing Test" were 0.15 percent by weight of the total detergent formulation.

Example 1 illustrates a suitable detergent formulation prepared from the sulfonated phenyl-n-alkane mixtures of the present invention.

EXAMPLE 1

A detergent formulation was prepared containing the following percentages of each ingredient, based on the total weight of the formulation:

Formulation, wt. percent		
50% C ₁₁ +50% C ₁₅ (internal)		24
Sulfonated phenyl-n-alkanes		
Sodium tripolyphosphate		40
Sodium silicate		7
Carboxymethylcellulose		1
Sodium sulfate		20
Water		8

The formulation was tested and found effective in accordance with the "Hand Dishwashing Test" for a rating of 18 plates.

Example 2 is an analysis of the mass distribution of the side chains in the C₁₁-C₁₄ sulfonated phenyl-n-alkanes used in subsequent evaluation.

[Mass distribution of side chains]		
Mass distribution of side chains	Weight, percent	Mole, percent
<C ₁₁	1.4	1.6
C ₁₁	9.4	10.3
C ₁₂	32.8	33.9
C ₁₃	33.3	32.7
C ₁₄	22.7	21.1
C ₁₅	0.4	0.4
Total	100.0	100.0
Average molecular weight	254	254

Table I, discloses the phenyl isomer distribution of the C₁₁ and C₁₅ alkylates of the present invention.

TABLE I
[Isomer composition of C₁₁ and C₁₅ alkylates and blends]

Ex.	Phenyl-n-alkanes	Straight-chain isomer distribution, weight percent			
		5-phenyl through 8-phenyl	4-phenyl	3-phenyl	2-phenyl
3	C ₁₁	10	13	27	50
4	C ₁₅ (internal)	84	11	4	1
5	C ₁₅ (end)	15	16	29	40
6	C ₁₅ (whole) ²	61	13	12	14
7	C ₁₁ -C ₁₄ ³	45	16	16	23
8	80% C ₁₁ -C ₁₄ ³ plus 20% internal C ₁₅	52	15	14	19
9	80% C ₁₁ -C ₁₄ ³ plus 20% whole C ₁₅	48	16	15	21

¹ Contains 6% C₁₄.

² Two parts internal/one part end; contains 4% C₁₁.

³ Sulfonated phenyl-n-alkane of Example 2.

Table II, illustrates the synergistic effect of the C₁₁-C₁₅ sulfonated phenyl-n-alkane blends of the present invention. It is noted that the synergistic effect for the C₁₅ internal isomers in Example 15 is almost double that of the C₁₅ whole isomers of Example 17.

TABLE II

[Dishwashing performance of 0.15% concentrations of formulations containing C₁₁ and C₁₅ sulfonated phenyl-n-alkanes (50 p.p.m. hardness)]

Ex.	Sulfonated phenyl-n-alkanes	Number of plates washed		
		Measured	Predicted (from graph)	Synergistic improvement
10	C ₁₁	8		
11	C ₁₅ (internal)	14		
12	C ₁₅ (end)	12		
13	C ₁₅ (whole)	12		
	C ₁₁ -C ₁₅ (internal) mixtures by weight:			
14	1:2	20	13	7
15	1:1	20	11	9
16	2:1	17	10	7
17	C ₁₅ (whole) 1/1: C ₁₁ -C ₁₅	15	10	5
18	C ₁₁ -C ₁₄ ²	20		
19	80% C ₁₁ -C ₁₄ ² plus 20% C ₁₅ (internal)	20	18	2
20	80% C ₁₁ -C ₁₄ ² plus 20% C ₁₅ (whole)	18	18	0

¹ 24/40/7/1/20/8 formulation.

² Sulfonated phenyl-n-alkane of Example 2.

Note.—See Table I for compositions.

While the character of this invention has been described in detail with numerous examples, this has been done by way of illustration only and without limitation of the invention. It will be apparent to those skilled in the art that modifications and variations of the illustrative examples may be made in the practice of the invention within the scope of the following claims.

What is claimed is:

1. A detergent alkylate composition comprising from about 10 to 85 percent by weight of secondary C₁₁ phenyl-n-alkanes and from about 15 to 90 percent by weight of secondary C₁₅ phenyl-n-alkanes.

2. A detergent alkylate composition as in claim 1, wherein from 50 to 100 weight percent of the C₁₅ phenyl-n-alkanes are the 5-, 6-, 7-, and 8-positional isomers.

3. A detergent alkylate composition as in claim 2, wherein the secondary C₁₁ phenyl-n-alkanes are present in an amount of from about 20 to 70 percent and the secondary C₁₅ phenyl-n-alkanes are present in an amount of from about 30 to 80 percent.
